By Clarence A. O'Brien, Attorney

UNITED STATES PATENT OFFICE.

WILLIAM HARGREAVES, OF LONG BEACH, CALIFORNIA, ASSIGNOR TO THADDEUS R. PRICE, OF BATESVILLE, TEXAS.

UNDERREAMER.

Application filed May 7, 1928. Serial No. 275,851.

The present invention relates to improvements in earth working implements and has reference more particularly to an underreamer.

5 One of the important objects of the present invention is to provide an underreamer that is adapted to be passed downwardly in a well casing, a series of reamer blades being pivotally and slidably associated at their upper ends with the body of the reamer, resilient means being interposed between the body and the lower free end portions of the blade for normally urging the same outwardly when the reamer blades are disposed below the 10 lower end of the casing, additional means being provided for locking the blades in lowered outwardly disposed position.

A further object of the invention is to provide an underreamer which includes a removable fish tail bit for association with the lower end of the body.

20 Still a further object is to provide an underreamer of the above mentioned character, which is simple in construction, inexpensive, strong and durable, and further well adapted to the purpose for which it is designed.

Other objects of the invention will become apparent as the nature of the invention proceeds, and when taken in connection with the accompanying drawings.

In the accompanying drawings:

Figure 1 is a side elevation of the underreamer embodying my invention, showing the 35 position of the blades, while the reamer is being passed downwardly through a well casing.

Figure 2 is a similar view, showing the position of the blades when the reamer body 40 is disposed below the lower end of the well casing, and also showing the manner in which the pivoted blades are locked in their outwardly disposed positions.

Figure 3 is a transverse section taken approximately on the line 3—3 of Figure 1, looking upwardly.

Figure 4 is a similar section taken approximately on the line 4—4 of Figure 1, looking downwardly, and

50 Figure 5 is a transverse section taken on the

line 5—5 of Figure 1, also looking in a downward direction, and

Figure 6 is a detail perspective view of one of the reamer blades, forming a salient part of the present invention.

In the drawings, wherein for the purpose of illustration is shown the preferred embodiment of my invention, the numeral 1 designates generally my improved underreamer, the same comprising an elongated solid body, 60 the intermediate portion of which is so constructed as to form the flat faces 3, three of such faces being provided, whereby a triangular formation is formed, as shown more clearly in Figures 3, 4, and 5 of the drawings. 65

As shown in Figures 1 and 2, these flat faces are not continuous, the same being interrupted at the intermediate portions thereof.

The lower end of the cylindrical body is formed with an internally threaded socket 4, 70 for receiving the threaded shank 5 of the fish tail 6, so that said bit can be readily attached or disengaged. The upper end of the body is formed with a threaded projection 7 for connection to the lower end of the drill rod, 75 in the manner well known in the art. The body of the reamer is formed with a fluid passage 8 in the upper end, and the same extends centrally through the threaded extension 7. Radial passages 9 extend from the 80 lower end of the central vertical passage 8, to the upper ends of the respective flattened faces 3, as clearly shown in Figures 1 and 3 of the drawings. The cylindrical portion of the body 2 that interrupts the intermediate 85 portion of each flat face 3 is formed with a longitudinal slot 11 that extends inwardly adjacent each flat face 3. The portion of the cylindrical body adjacent each flat face is further formed with a similar slot, indicated 90 at 12, and the purpose of these slots will also be presently apparent.

The under reamer further includes the provision of a series of reamer blades, one of which is shown in detail in Figure 6. Each 95 blade which is designated generally by the numeral 13 is of a flat piece of metal and comprises the blade or earth engaging portion 14 from which extends upwardly the elongated shank 15. The lower end of the earth engag- 100

ing portion of the blade is cut away as at 16, and an enlargement 17 is formed at the inner edge portion of the earth engaging portion 14 at the upper part thereof and an angular slot 18 is formed in the enlarged portion 17. A longitudinally extending slot 19 is formed in the upper end portion of the shank 5 and as is further shown in Figure 6, the upper end of the shank is slightly rounded. These blades 10 are disposed against the respective flat faces of the body 2, and the shank portion 15 is adapted for disposition within the slot 11, while the lower end portion of the blade section 14 is adapted for disposition in the slot 15 12 and this arrangement is clearly illustrated in Figures 1 and 2 of the drawings. The headed pin or screw 20 is threaded into a threaded opening provided therefor in each flat face, adjacent the upper end thereof and 20 the shank of each screw extends through the slot 19 of the respective blade, and thus provides a slidable and pivotal connection for the upper end of each reamer blade on the body 2.

Additional headed bolts 21 are threaded in 25 threaded sockets provided therefore in the respective flat faces 3 at a point below the cylindrical portion 10 which intersects the flat faces, and these headed pins or bolts 21 are operable in the slots 18 of the respective reamer blades for a purpose also to be presently described in detail.

Also secured on this portion of each flat face 3 is a stop forming lug 22 for engagement with the inner edge of the lower portion 35 of the shank of each blade to limit the inward swinging movement of the reamer blades.

The earth engaging portions 14 of the pivoted blades are normally urged outwardly by the action of the leaf springs 23. One leaf 40 spring is provided for each blade and the upper end of the leaf spring is secured within a suitable recess provided therefor in the lower portion of the shoulder 10, the lower end of each spring being bowed inwardly for engagement with the inner edge of the shoulder 45 or enlargement 17 of the blade, as indicated in the drawings.

When the underreamer is in the act of being lowered downwardly in the well casing 50 A, the blades 13 are in their lowermost position, so that the headed bolts 20 will be disposed in the uppermost ends of the slots 19, while the headed bolts 21 will be in engagement with the outer ends of the horizontally 55 disposed portions of the angular slots 18 and the blades will be confined within their respective slots, by reason of the inner wall of the well casing engaging the outer edges of the blade, as clearly shown in Figure 1.

As soon as the underreamer passes beyond 60 the lower end of the well casing, the springs 23 will force the pivoted reamer blades outwardly to an operative position and a further downward movement of the body of

the reamer will result in the bolt 20 moving 65 downwardly to the lower end of the slot 19 and in the meantime, the headed bolt 21 will have been moved to the lower ends of the vertical portions of the angular slots 18, thus positively locking the blades in their outwardly disposed position and ready for use.

By raising upwardly on the body 2, the bolt will again assume the position shown in Figure 1, so that when the reamer is pulled upwardly through the well casing, the well casing will move the pivoted reamer blades inwardly for disposition in the respective slots and hold the same in the position also shown in Figure 1, whereby to permit the ready and easy removal of the reamer after the same has 80 performed its drilling operation in the well formed in the ground.

It will thus be seen from the foregoing description that I have provided an underreamer that will permit the pivoted reamer 85 blades to be moved inwardly and outwardly to an inoperative and operative position respectively, in an automatic manner, and furthermore, the locking means will also be automatic. The simplicity of my improved 90 underreamer enables the same to be constructed at a very low cost, and the parts can be readily replaced whenever necessary without requiring the complete destruction of the underreamer.

While I have shown the preferred embodiment of my invention, it is to be understood 95 that various changes in the size, shape and arrangement of parts may be resorted to, without departing from the spirit of the invention and the scope of the appended claim.

Having thus described my invention, what I claim as new is:

In an underreamer of the class described, 105 an elongated body having a series of flat elongated faces, upper and lower shoulders formed on each flat face, said shoulders being slotted longitudinally adjacent the respective flat face of the body, a plurality of reamer blades each including an earth engaging portion, an upwardly extending shank, the shank being formed with a longitudinal slot in its upper end, the earth engaging portion being provided with an angular slot adjacent its inner edge, headed bolts threaded into the upper portions of the respective flat faces of the body for disposition within the respective longitudinal slots formed in the shank portions of the blades, additional headed bolts 115 threaded into the flattened faces of the body for disposition within the respective angular slots, said blades being operable within the slots formed in the shoulders on the respective flattened faces of the body and being capable 120 of outward swinging movement to an operative position when the last mentioned headed bolts are disposed in the forward ends of the horizontal disposed portions of the annular 125

slots, leaf springs secured at their upper ends in the lower portions of the respective shoulders, the free ends of the leaf springs bearing against the inner edge portions of the

5 respective earth engaging portion of the blades to urge the same outwardly with respect to the body, said last mentioned headed

bolts being disposed in the lower portions of the angular slots to lock the blades in an outwardly disposed operative position when the 10 body is moved downwardly.

In testimony whereof I affix my signature.

WILLIAM HARGREAVES.
